UNITED STATES PATENT OFFICE

2,107,646

BURNER

Thomas E. Potts, Los Angeles, Calif.

Application March 31, 1936, Serial No. 71,853

3 Claims. (Cl. 158—91)

This invention relates to devices in which liquid fuels as well as gases can be burned.

One of the objects of this invention is to provide a burner of this type so designed that the air supply can be controlled at the very point at which the fuel is brought to a state of ignition and so that an intermixing of air with fuel is forced at this point.

Another object is to provide for a circulation of the products of combustion inside and outside about the whole burner.

Another object is to provide for a convenient observation of the burner.

Another object is to provide for a convenient regulation of the burner under a close observation.

Other objects will appear from the following description and appended claims as well as from the accompanying drawing, in which—

Fig. 1 is a perspective view of the complete burner, though without fuel connections and controls.

Fig. 2 is a top plan view of the lower pan.

Fig. 3 is a vertical longitudinal midsectional view of the burner with the top combustion control and front air control in proper position.

Fig. 4 is a vertical section on line 4—4 of Fig. 3.

Fig. 5 is a vertical section on line 5—5 of Fig. 2.

This burner is especially designed for small heating plants, even, particularly, for such small devices as so-called air-tight heaters.

The illustrations of Figs. 1 and 2, by means of the flanges 6, make it clear to what extent this burner is outside or inside of a heating plant, the whole control parts being outside and the combustion parts being inside of such plants.

Having already stated that liquid as well as gas fuel is to be used with this burner, there are, in the first place, the supply connection 8 for the liquid fuel and the connection 7 for the gas fuel, secondly, the control valve 9, but, furthermore, the air control means for the combined burner, consisting of the top plate 10, extending to the outside and covering that whole portion over the top of the burner that is in front of the flanges 6, and the inwardly extending portion 12, by which the air supply can be controlled and checked, the whole air control means being handled by the lug 11 on the top portion 16 to be adjusted with respect to the inside combustion chamber.

The inwardly extending portion 13 of the main pan serves as a mixing and combustion chamber. In Fig. 3, for instance, the portion 12 of the air control means forms some sort of a baf-

file by which the inrushing air is checked and deflected downwardly to intermix with the fuel normally injected near the bottom of the main pan below the lower edge 14 of the baffle, this edge being designed and so arranged that it will come in close proximity of the surfaces 15 of the raised bottom portions 16 in the position in which the baffle checks the inrushing of the air in the extreme, being the position in which the air control is withdrawn to the outermost 10 position within the main pan.

There is a central channel 17 below the surface 15, and this channel is even reduced at the most critical point, at which the leanest mixture of air and fuel is to be produced, by additional 15 raised portions 18 to form a still smaller central channel 19, as will be more clearly understood from the illustration in Fig. 3 taken together with the illustration of Fig. 5.

With this setting of the baffle 12, the combustion chamber extends then from the baffle rearwardly to the rear wall 20 of the main pan, and crosswise between the side walls 21.

This setting also limits the passage for the combined air and fuel that enters the combustion chamber to the reduced cross section of this central channel.

Considering then the illustration of Fig. 2, it will at once become evident that, by an inward shifting or adjustment of the air control means in the direction towards the rear wall 20 of the main pan, the area of the central passage is gradually increased from the very point at which the cross section 5—5 is taken as the edge 14 of the baffle 12 passes over the raised portions 16, being 35 beveled off towards the rear, as indicated at 22, in such a manner as to give this result as will be understood.

The air control member is for this reason mounted in the upper edge of the side walls in 40 suitably shaped recessed shoulders, indicated at 23 in Fig. 2, and from the illustration in Fig. 3 it must be clear that the top plate 10 is sufficiently shorter than the recessed shoulder 23 to facilitate such a shifting and adjustment of the air control member in and to a limited extent, but so that a sufficient amount of air can be admitted for a proper and desired mixture of different fuel and for the different intensities at 45 times required in a burner.

A heat distributing member 24 is provided in a certain relation to the combustion chamber, as illustrated in Figs. 1, 3 and 4.

This distributing and circulating member 24 is provided with top baffles 27 and side baffles 55

28, having lugs 25 and 26 suitably disposed to support the member 24 so that the top baffles become spaced above the top edge and the side baffles become spaced beyond the outside faces 5 of the side walls 21 of the rearwardly extending combustion chamber, in such a manner that a circulation and distribution of the products of combustion and therewith of heat may be had partly through the top in the direction of the 10 arrows 28 and partly in the directions of the arrows 29, suitably around the outside of the combustion chamber, to facilitate a superheating of the fuel in the combustion chamber.

It must be understood that the flanges 27 and 15 28 may be wider or narrower, to suit different conditions, due to different locations and fuels.

I claim:

1. In a burner, a main pan having connections 20 for discharging liquid and gas fuels into the pan, an air control member shiftably mounted in the pan and embodying a top portion designed to close off the top of the front portion of the pan and a baffle portion extending downwardly between said connections and rearmost portion of 25 the pan leaving a space above the bottom of the pan so that fuel and air can pass below the baffle into said rearmost portion, the pan having a bottom portion with rearwardly spreading shoulders so that various amounts of air can 30 pass under the baffle when shifted towards the rearmost portion.

2. In a burner, a main pan having connections for discharging liquid and gas fuels into the pan, an air control member adjustably mounted on the pan shiftable from front to rear, the pan having a bottom portion with rearwardly spreading shoulders to allow various amounts of air to pass from the front towards the rear under the air control member, and a heat distributing member disposed over the rear portion of the pan having flange-like portions over the 10 top leaving an open discharge space over the top of the pan and being spaced above the top edge of the pan and with flange-like portions extending downwardly from the first-named flange-like portions and being spaced laterally from the 15 pan for circulating a part of the products of combustion around the pan for heating the fuel in the pan.

3. In a burner, a main pan having connections 20 for liquid and gas fuels, an air control member embodying a top plate and a baffle portion, the pan having a bottom-portion with a top surface and fuel passing means of varying cross-sectional areas extending below such surface, the pan having also means in its top portion for shiftably 25 supporting the member so that the baffle and bottom portion form an outlet fuel and air passage of varying cross-sectional areas as the baffle is shifted back and forth.
